UNITED STATES PATENT OFFICE

2,494,377

DUMP TRUCK

Anthony L. Cresci, Vineland, N. J.

Application December 11, 1945, Serial No. 634,320

2 Claims. (Cl. 298—11)

1

The present invention relates to dump trucks, particularly to mechanism for hoisting the truck body.

It is desirable for some purposes, such as the delivery of coal and loads of a similar character, that the truck body be elevated to a relatively great height and at the same time that the body be tilted to such an angle that the load will be readily discharged by gravity. This invention provides for such "high-lift" and includes, in addition to the usual pivoted crossed levers and hydraulic hoist mechanism, auxiliary hoisting apparatus designed to elevate and tilt the body to effect a higher lift and greater dumping angle of the truck body.

It is one of the objects of the invention to provide additional lift cylinders connected to the fluid supply of the main hoisting mechanism and acting on the front end of the body further to elevate and tilt the body.

It is another object of the invention to provide an arrangement of fluid supply lines and valves therefor to control the auxiliary as well as the main hoisting mechanism.

Other objects will be apparent from the following description of the invention taken in connection with the accompanying drawings, in which

Fig. 1 is a side elevation of a preferred embodiment of the invention, certain of the parts being broken away better to illustrate the controls;

Fig. 2 is a front elevation of the body showing the positions of the auxiliary lift cylinders, part of the underframe being broken away to illustrate the manner in which the cylinders are pivoted to the body and to the underframe;

Fig. 3 is a fragmentary diagrammatic plan of the hydraulic system and the valves for controlling its operation.

In the drawings, the vehicle chassis or main frame 10 supports, by means of pivoted crossed levers 11 and 12, the sub-frame 13 on which body 14 is pivotally mounted as by pins 15 adjacent the rear end of the sub-frame. Toggle links 16 and 17 connect lever 11 to the chassis, link 16 being pivoted on the chassis and link 17 being pivotally connected to the lower end of lever 11, the upper end of which is pivoted to sub-frame 13 at 18. Link 19 connects the upper end of lever 12 to the sub-frame, the lower end of lever 12 being pivoted on the chassis. Levers 11 and 12 are connected to each other by a pivot rod 20.

The hydraulic hoisting mechanism which effects simultaneous elevation and tilting of the sub-frame, comprises cylinder 21, pivoted on chassis 10 at 22, and the ram or piston 23, pivot-

ally connected to the pivot rod 20. A source of fluid under pressure, which may be oil or some other suitable fluid, includes a tank 24 and pump 25, the oil or other fluid being pumped from tank 24 to cylinder 21 by pump 25 to elevate the crossed levers and the body connected thereto. The pump is driven from the vehicle motor through a clutch 26 and shaft 27, suitable universal joints 28 being interposed between the clutch and the pump.

Adjacent each corner at the front of the sub-frame and independent of the main hoisting mechanism is an auxiliary cylinder 29 and a piston 30. Since these cylinders, pistons and their mountings are similar, only one of them will

be described. Attached to each of cylinders 29 is a ring 31 having diametrically opposite recesses 32 to accommodate pins 33, the latter also passing through openings 34 in the sub-frame so that the cylinder is swingably mounted on the sub-frame.

20 A pair of recessed fulcrum blocks 35 are welded or otherwise secured to longitudinal frame member 36 of the body, and to bracket 37 fastened to frame member 36, pin 38 passing through these blocks and through a recess 39 in the upper end 25 of piston 30. It will thus be seen that piston 30 is mounted for swinging movement with respect to body 14.

The means for controlling the supply of fluid under pressure and the return of the fluid to the supply tank are shown in Figs. 1 and 3. Assuming the body is to be lifted, the valve 40 between tank 24 and the discharge side of pump 25 is first closed. Fluid under pressure then flows through connection 41 to cylinder 21, forcing piston 23 in a direction to elevate the body. At this time valve

30 42 may be open or closed, depending on whether it is desirable to employ the auxiliary hoist before or after complete elevation of the main hoist. When valve 42 is open, it will be seen that fluid

under pressure will also be supplied to cylinders 29 through flexible connections 43, 44, in which case the body will be tilted about pins 15 further to increase the dump angle of the body. Check valve 45 is interposed between the discharge side

40 of pump 25 and the hoist cylinders to maintain pressure in the lines after the pump has been stopped, the body being thus held at the desired height whether it be complete or only partial elevation.

45 To lower the body, the pump is disconnected from the motor by throwing out clutch 26, and valves 40, 42 opened. The weight of the body is sufficient to force the motive fluid out of the cylinders and return it to storage tank 24. Since the pressure exerted by piston 23 will be greater

than that in cylinders 29 during the lowering of the body, the crossed levers will first return to their lowermost positions, whereupon the weight of the body will force fluid from the auxiliary cylinders. The body and sub-frame will then rest on the chassis in parallel relation thereto.

From the foregoing description it will be apparent that it is possible to elevate a dump truck body to a relatively great height and at this height to tilt the body to a greater dump angle than that resulting from the elevation by the main hoisting mechanism. Since there are limitations to the angle to which the body may be tilted by the conventional combined hoisting and tilting mechanisms, it is obvious that the auxiliary tilting device provides means to facilitate and accelerate the unloading of the body.

While a preferred embodiment of the invention has been illustrated and described, it is to be understood that it is susceptible of modification and is not to be limited to the exact arrangement of parts shown in the drawings.

Having described my invention, what I claim as new and desire to secure by Letters Patent is:

1. In combination, a dump truck including a main frame, a sub-frame and a body, said sub-frame being movably supported on said main frame and said body being pivotally mounted on said sub-frame adjacent the rear end of the sub-frame, a source of fluid under pressure, means operated by fluid under pressure from said source for simultaneously elevating and tilting said sub-frame with the front end of the sub-frame at a greater height than that of the rear end of the sub-frame, a cylinder pivoted to said sub-frame, a piston in said cylinder and pivoted to said body, and means for supplying fluid under pressure

4
from said source to said cylinder for raising only the front end of said body with respect to said sub-frame.

2. In combination, a dump truck including a main frame, a sub-frame and a body, a pair of crossed levers, each of said levers having a pivotal connection at one end with said main frame and a pivotal connection at its other end with said body, a source of fluid under pressure, a cylinder connected at one end to said main frame, a piston in said cylinder and pivoted to said crossed levers, means for supplying fluid under pressure from said source to said cylinder for simultaneously elevating said levers and tilting said sub-frame in one direction, a pivotal connection between said sub-frame and said body, an auxiliary cylinder pivoted to said sub-frame, a piston in said auxiliary cylinder and pivoted to said body, and means for supplying fluid under pressure from said source to said auxiliary cylinder for tilting said body in said one direction with respect to said sub-frame.

ANTHONY L. CRESCI.
